7801 X John Elgar.

The schedule referred to in this Letter Patent, and making part of, the same containing a description in the words of the said John Elgar himself of his improvement in the wheels of Rail-Road carriages.

To all whom it may concern,

Be it known, that I, John Elgar, Civil Engineer, of the city of Philadelphia, have invented certain improvements in the wheels of Rail-Road carriages, by one of which improvements, they are made to adapt themselves more readily to curved roads than such as have heretofore been used for that purpose, and by the other a construction is given to them which will render them more firm and durable than those now in general use, and I hereby declare that the following is a full and exact description of my said improvements. — The self-adjusting conical wheel, for running upon curved roads, is well known to engineers, it having been made the subject of a patent by James Wright, and a modified form of it, being now used on the Baltimore and Ohio Rail-Road. The plan which I have devised is a new modification of this principle, by which some of the inconveniences which have hitherto attended its employment are, in a great degree, if not altogether obviated. — Instead of making the wheel conical, or its whole tread, like Wright's, or of forming the conical part against the flange, and leaving the other part cylindrical, as is done, and on the Baltimore Road, I form the cone on the outer part of the tread of the wheel, opposite the flange, leaving that part of the tread which extends upon the flange towards the opposite side cylindrical, or nearly so, for one half of its width, more or less, and then tapering outward in such degree as may be found most economical, according to the curvature of that part of the road, which has the smallest radius. — The conical part of the wheel is adapted to these wheels by widening the track in proportion to the radius of curvature, so as to admit the conical part to roll on the inner

1801 X

terior rail, whilst the cylindrical part bears upon the exterior rail. This construction obviates the objection arising from the wrong tendency of the cone when running on the exterior rail and adapts the wheel more perfectly to these parts of the road, you straight, and produces other advantages which will readily occur to experienced engineers.

In order to render rail and wheel more firm and durable than they now in use, I propose that part of the wheel usually occupied by the spokes, of two plates of iron, preferring for this purpose thick sheet iron of three eighths of an inch, more or less, in thickness. These sheets of iron are raised so as to be concave, or dishing, forming the segment of a large sphere, or if preferred, they may be made conical. These plates have a hole in their centres to receive the hub, or nave, and have a flange turned up, over which the hoop of the hub may pass, or the hub may be secured in other way if preferred. If the rim, or tire, is of wrought iron, the plates may have a flange turned at their peripheries, this which they may project on the interior of the rim. When the rim is of cast iron, the plates may be secured without a flange, one being cast within the rim, against which the plate may fit, on either side, & bolts, or bolts passing through and this, the flange to secure them in their places. Other modes of fixing the plates in their places may be devised, and I do not mean to confine myself to any specific plan of effecting this object, the manner of doing so, not in any way affecting the principle upon which my improvement is founded.

What I claim as my invention is, my first described improvement is, making the wheel of a railway carriage conical on its outer edge, and cylindrical between said conical part and the flange, for the purpose of adapting it to run on curved roads, and applying it thence upon the principles and in the manner hereinbefore set forth. What I claim as my invention in my second described improvement, is the substituting of metallic plates (generally of wrought iron) for the spokes usually employed, and giving to such plates a form which shall be concave, either curved or conical, from the rim to the hub of the wheel.
